UNITED STATES PATENT OFFICE.

EUGEN ALBERT, OF MUNICH, GERMANY,

PROCESS FOR MAKING AUTOTYPE PRINTING-BLOCKS.

No. 926,377.

Specification of Letters Patent.

Patented June 29, 1909.

Application filed July 23, 1908. Serial No. 444,935.

To all whom it may concern:

Be it known that I, EUGEN ALBERT, a subject of the Emperor of Germany, residing at Munich, in the Kingdom of Bavaria, Germany, have invented certain new and useful Improvements in Processes for Making Autotype Printing-Blocks, of which the following is a specification.

This invention relates to an improved process for making auto type printing blocks and has for its object to improve the dot formation thereon so as to make the tones of the picture printed therefrom more perfectly like those of the original picture than have heretofore been obtained. It is well known that such blocks—usually called half tone blocks—are printed through a finely divided glass screen and in order to obtain the breaking up of the light values of the half tone negative into points and lines of suitable dimensions it has hitherto been proposed that during, prior to, or after the copying of the negative, the screen should not bear directly upon the sensitive layer, but be placed at a slight distance away and the angle of incidence of the light changed. It should be noted in this connection that the rays of light are always regarded as parallel in themselves owing to the minuteness of the screen aperture and to the slight distance of these from the sensitive layer in proportion to the great distance of the source of light.

Usually the process mentioned when using a cross screen was carried out by altering the angle at which the plane of the screen and the sensitive plate stood with reference to the source of light; the axis of the annular oscillation had either to form an angle with the line systems of the screen, or else be parallel to one of the systems; in neither case was the point form satisfactory, in fact a correct point form with concentrically increasing light intensities, and which is also capable of properly reproducing the light values of a negative, or positive, cannot be obtained at all with cross screens by alterations of the angle merely, at which they stand with reference to the source of light.

This invention consists in arranging that the projection of the transparencies of the cross screen upon the sensitive coating is effected at angles lying in several planes with regard to the source of light and in making the angles of coincidence of the rays of light as small as possible, I having discovered that the smaller the angles and the more planes

there are the softer is the decline of the curve of intensity of the dot, and as a result the richer are the tones of the reproduction. The reduction of the angles at which the rays of light fall on the sensitive surface is achieved in such a way that the action of the perpendicular rays of light, and of those nearly perpendicular, is materially diminished.

In practice very good results have been given by arrangement such that the central point of the projection described an annular path, the maximum diameter of which is preferably not larger than one side of the projected screen transparency and, if the annular path forms a circle, then allowance must be made for one and the same equal degree of the angle of incidence of the rays of light at each point of the path and in an infinite number of planes. Apparatus for carrying this process into effect is fully disclosed in my co-pending application, Ser. No. 444,934, filed July 23/08.

Figures 1-3 of the accompanying drawings will serve to explain the process diagrammatically.

In Fig. 1 the square shows the projection of a screen aperture, greatly magnified and the circle the ring in which the central point of the projection is to move. In order to give a bird's eye view of the matter only 12 points 1-12 are given in the ring, and by the successive displacement of the central point of the square there is produced in place of these 12 points the figure 2, in which the copying intensities are given by means of figures. From these figures there is obtained the form of the decline of the intensity curve, the field marked 12 is of the greatest intensity, the diminution being radially outward through fields 11 to 1 inclusive. As regards the shape of the dot it is clear that the corners on the outer sides will disappear by increasing the number of the points of displacement; by continued operation there is obtained the form shown by dotted lines in Fig. 3, at four adjacent screen points 12 denoting the centers of the points. If the annular path is exactly a circle then round shaped screen points are formed, but if on the contrary it is somewhat lengthened, then the so-called egg shape, or oval bar shape is obtained.

The means employed in practice for causing the screen point projection to follow the required annular path are numerous; this re-

sult may be attained by moving the source of light in an annular path in a plane parallel to the plane of the screen, or preferably by moving the copying frame itself in such an 5 annular path.

What I claim as my invention and desire to secure by Letters Patent is:—

1. The process of making auto type printing blocks from half tone negatives or positives by means of cross screens, which consists in effecting the projection of the transparent spaces of the cross screen upon the sensitive layer of the block, during the copying process in a multiplicity of different non 10 parallel planes with reference to the source of light, the projection of each space thereby progressing along a continuous path, such projection being effected with total or nearly total extinction of the action of the rays 15 of light falling on the surface in angles which are perpendicular, or nearly perpendicular, thereto.
2. The process of making auto type printing blocks from half tone negatives or positives by means of cross screens, which consists in effecting the projection of the transparent spaces of the cross screen upon the sensitive layer of the block during the copying process in a multiplicity of different non- 20 parallel planes with reference to the source of light, the projection of each space thereby progressing along a continuous path, such projection being obtained by rays of light falling on the 25 screen at very small angles of incidence, and with total or nearly total extinction of the action of the rays of light falling on the surface in angles which are perpendicular, or nearly perpendicular, thereto.
3. The process of making auto type printing blocks from half tone negatives or positives by means of cross screens, which consists in effecting the projection of the trans- 30

parent spaces of the cross screen upon the sensitive layer of the block during the copying process by altering in different directions the relative positions of the screen, the sensitive surface and the source of light so that the central points of the projections of the transparent spaces of the screen form a closed annular shaped path, the maximum diameter of which is not substantially larger than one side of the projected transparent space.

4. The process of making auto type printing blocks from half tone negatives or positives by means of cross screens, which consists in effecting the projections of the transparent spaces of the cross screen upon the sensitive layer of the block during the copying process by causing the screen and the sensitive surface to follow an annular path with reference to a fixed source of light such that the central point of the projection of each transparent space of the screen upon said sensitive layer forms a closed annular shaped path the maximum diameter of which is not substantially larger than one side of the projected transparent space.

5. The process of making autotype printing blocks, from half tone negatives or positives by means of cross-screens, consisting in projecting, during the act of copying, the light transmitted through each transparent space of the cross-screen upon the sensitive layer of the block in a multiplicity of successive positions in a curvilinear path and within an area not greater in extent than that of such transparent space.

In testimony whereof I affix my signature & in presence of two witnesses.

EUGEN ALBERT.
